UNITED STATES PATENT OFFICE.

LILY B. SMITH, OF ATLANTA, GEORGIA.

RETAINING MEANS FOR SHOE-LACES.

1,306,840.

Specification of Letters Patent. Patented June 17, 1919.

Application filed December 27, 1918. Serial No. 268,540.

To all whom it may concern:

Be it known that I, LILY B. SMITH, a citizen of the United States, residing at Atlanta, in the county of Fulton and State of Georgia, have invented certain new and useful Improvements in Retaining Means for Shoe-Laces, of which the following is a specification.

It is well known that persons, after lacing their shoes and in order to present a neat appearance, tuck the free ends of the laces in the tops of the shoes. These lacing ends are usually provided with metallic tips which, when tucked in the tops of the shoes directly next to the stockings, cut the threads of the stockings and soon form holes and "runners." This state of affairs is common with ladies who wear high laced shoes and expensive silk stockings.

One object of my invention is to provide means whereby the tipped lace ends can be tucked and concealed within the shoes without in any way injuring or impairing the stockings.

Another object is to so construct my invention that the application thereof to a shoe will not render the shoe uncomfortable to the wearer.

A still further object is to so design my invention that it can be cheaply and quickly applied to shoes.

These objects, and other advantageous ends which will be described hereinafter, I attain in the following manner, reference being had to the accompanying drawings in which—

Figure 1 is a perspective view of a lady's high laced boot or shoe having my invention thereon,

Fig. 2 is an enlarged section taken on the line 2—2 of Fig. 1,

Fig. 3 is a sectional view taken on the line 3—3 of Fig. 2,

Fig. 4 is a view of similar nature to Fig. 2 showing the tipped end of a shoe lace occupying a different position and arrangement from that of the tipped lace end illustrated in Fig. 2,

Fig. 5 is a fragmentary elevation, partly

in section, showing a modified form of my invention,

Fig. 6 is a fragmentary section taken on the line 6—6 of Fig. 5,

Fig. 7 is a view of similar nature to Fig. 5 showing another modified form of my invention,

Fig. 8 is a fragmentary section taken on the line 8—8 of Fig. 7,

Fig. 9 is an outside elevation of a portion of a shoe showing another modification of my invention,

Fig. 10 is a section on the line 10—10 of Fig. 9,

Fig. 11 is a view of similar nature to Fig. 9 showing still another modified form of my invention, and

Fig. 12 is a section taken on the line 12—12 of Fig. 11.

Referring to Figs. 1 to 4, inclusive, 15 represents the upper of a shoe which has an 70 inner facing band 16 secured therein at the top of the upper by rows of stitching 17 and 18 (Fig. 3). The portion 19 of the band 16, between two substantially vertical rows 20 and 21 of stitches, is free of the upper, as 75 clearly shown in Figs. 2 and 3. This portion 19 is split or cut through its entire thickness by parallel cuts 22 and 23, said cuts terminating between the rows of stitching 17 and 18.

By this arrangement and treatment of the above mentioned parts, a portion 24 of the band 16 is provided which can be bulged inwardly in the form of a loop and the tipped ends 25 of the shoe lace can be inserted 85 through entrances formed by the cuttings 22 and 23, so that the end of the lace can be housed between the inner facing band 16 and the upper 15.

The spaces 26 and 27 between the facing 90 band 16 and the upper 15 provide pockets into which the tips of the shoe laces can be inserted after passing behind the loop 24, as clearly shown in Figs. 2 and 3.

In Fig. 4 I have shown the same arrangement and construction of parts but a different arrangement of the shoe lace. For example, if the tipped end of the lace is ex-

ceptionally long, the entire lace can be first passed through the cutting 23, then back of the loop 24 and out of the cutting 22, and then folded upon itself and reinserted 5 through the cutting 22 so as to be positioned directly back of the loop 24, as illustrated in Fig. 4.

The band 16 is preferably made of soft but strong flexible material such, for example, as leather and, as shown in Fig. 1, the band can include two of the loops 24, one at each side of the laced parting 28 of the shoe.

In the modification of my invention shown in Figs. 5 and 6, I provide the inner surface 15 29 of the shoe upper 30 with a loop 31 which corresponds in function to the loop 24 above described. In this form of my invention, the loop 31 is an independent member which is stitched at its top and bottom by rows of 20 stitches 32 and 33 and the tips of the shoe laces can be inserted within the space 34 provided between the loop 31 and the inner surface 29 of the upper; it being noted that the space 34 is open at the side edges of the 25 loop 31 so that the tipped shoe lace can be inserted from either side.

The form of my invention shown in Figs. 7 and 8 is substantially similar to that described in Figs. 5 and 6 and consists of a 30 loop 35 of flexible material which is stitched adjacent its bottom by a row of stitching 36 to the inner surface 37 of the shoe upper 38. This loop 35 can be opened at its top and is attached adjacent its top to the upper 38 by 35 means of a snap-button 39. With this arrangement, the loop 35 can be opened at its top to permit the lace tip to be inserted and then snapped in the position shown in Fig. 8.

In the form of my invention shown in 40 Figs. 9 and 10, I have shown a strip 40 of flexible material which straddles the upper edge portion 41 of the shoe upper 42 and the opposite ends of the strip are jointly provided with a snap-button 43, the parts of 45 the snap-button being respectively secured to the end portions of said strip and are adapted to engage each other through the medium of a hole 44 provided in the upper 42. In this construction, the part 45 of the 50 strip provides a loop and the shoe lace can be inserted within the space 46 between the inner surface of the upper and said part 45.

The form of my invention shown in Figs. 11 and 12 is substantially similar to that 55 shown in Figs. 9 and 10 and consists of a strip 47 which straddles the upper edge portion 48 of the shoe upper 49. The strip 47 has one portion 50 secured to the inner surface 51 of the shoe upper 49 by stitching 52. The other end portion 53 of said strip portion 60 is provided with one part of a snap-button 54, the other part of said snap-button being secured to the outer surface 55 of the shoe upper. With this arrangement, the

part 53 can be released and raised until the 65 free portion 56 of the part 50 will be moved to permit the shoe lace to be inserted within the space 57 after which the part 53 can be again attached by means of the snap-button 54.

In each of the forms of my invention a flexible loop or pocket of soft strong material is provided which will not injure the stocking. By the use of my invention, therefore, a shoe can be kept neat in appearance 75 and at the same time stockings will be saved, for the reason that the metallic tips at all times will be housed and protected against direct engagement with the stocking.

While I have described my invention as 80 taking a particular form, it will be understood that the various parts of my invention may be changed without departing from the spirit thereof, and hence I do not limit myself to the precise construction set 85 forth, but consider that I am at liberty to make such changes and alterations as fairly come within the scope of the appended claims.

Having thus described my invention, what 90 I claim as new and desire to secure by Letters Patent is:

1. A lace retaining device including means secured to the upper of the shoe, said means being cut to provide an entrance for the shoe 95 lace tip between said means and the upper, whereby the entire tip can be housed; said means providing a pocket jointly with said upper and at one side of said cutting; substantially as described.

2. A lace retaining device including facing means for the upper of a shoe and being cut therethrough to provide a pocket for the end of the lace; and securing means for attaching said first means to the upper and 105 forming a termination of said pocket; substantially as described.

3. A lace retaining device including an inner facing band stitched adjacent its top and bottom edges to the inner surface of the 110 upper, whereby the portion between said stitching is free of the upper, said band being cut transversely to said stitching to provide an entrance for the end of the shoe lace between said band and the upper; substantially 115 as described.

4. A lace retaining device including an inner facing band stitched adjacent its top and bottom edges to the inner surface of the 120 upper, whereby the portion between said stitching is free of the upper, said band being cut transversely to said stitching to provide an entrance for the end of the shoe lace between said band and the upper; and rows 125 of stitches substantially parallel to said cutting, whereby pockets are formed jointly by said band and upper and at the side of said cutting; substantially as described.

5. A lace retaining device including means providing a flexible pocket having an entrance through which the end of said lace can be inserted so as to be housed by said pocket, said pocket being closed at a portion opposite to said entrance; substantially as described.

In testimony whereof I have signed my name to this specification in the presence of two subscribing witnesses.

LILY B. SMITH.
